CONTACT WHEEL, MAINLY FOR FINISHING
BELTS

William J. Cosmos, Chicago, Ill.

Application May 10, 1951, Serial No. 225,654

2 Claims. (Cl. 51—141)

1

This invention relates to segmental contact wheels for abrasive belts; mainly for service in buffing, burnishing, polishing and other finishing work.

This application is a continuation in part of my copending application S. N. 196,916 filed November 21, 1950, now issued as Patent No. 2,581,754, and mainly of the disclosure illustrated in Figures 17 to 19 of that application. The invention provides an improved molded disc unit for contact wheels of the type as indicated.

The art is familiar with the use of pleated or ruffled cloth, laminated to form buffing wheel discs which are directly covered with abrasive material. The art also knows buffing wheel or grinding wheel discs similarly covered but molded with radial corrugations, nested together to form a solid working surface. For instance this is shown in A. J. Doermann's Patent No. 1,912,069. Such a working surface of a buffing or grinding wheel has the advantage that it prevents the "marking" of the work piece. "Marking" occurs when abrasive particles are embedded in the rim of a segmental grinding or buffing wheel at or near a joint between segments and if the joint extends in the plane of rotation of the wheel.

It has occurred to me that a somewhat similar problem of contact wheels for abrasive belts can be resolved by a somewhat similar, corrugated rim design.

The preferred contact wheel which I have provided, and which I have found most efficient in actual finishing practice, has a rim with spaced parallel, continuous, Z-patterned working areas. Such areas can be formed by incorporating fan-shaped folds or corrugations in the rim and generally nesting them together but spacing the side surfaces of the folds. This wheel actuates an abrasive belt in a manner which prevents "marking" of the work piece; it also adds materially to the effective life of the belt, and it facilitates the adjustment of amounts of material removed from the work piece, and the selection of abrasive belts suitable for different types of work.

All this will be understood more clearly upon consideration of the detailed description which follows. In the drawing appended hereto, Figure 1 is a perspective diagram of a contact wheel according to this invention. Figure 2 is a side-view of this wheel. Figure 3 is an enlarged, 50 cross-sectional elevation of a disc unit or segment according to this invention, diagrammatically indicating its mounting and assembly. Figure 4 is an endview of this segment. Figure 5 is a more enlarged, partial endview of the wheel. Figures

6, 7 and 8 show modified wheels in views similar to Figure 5.

A belt A, coated with relatively fine abrasive granules, is driven in direction B by the contact wheel or actuating device C, composed of generally disc-shaped segments D. Each segment has a relatively flexible rim E consisting in generally fan-shaped folds or corrugations. In the central part of the contact wheel there is a central, circular opening F for the drive shaft G, preferably with a bushing H interposed. The contact wheel is secured to the drive shaft by a nut J, engaging screw threads K on one end of the shaft and pressing the contact wheel against a shoulder L on the shaft opposite the screw threads. Washers or end plates M may be interposed between the contact wheel and the shoulder, and between the contact wheel and the nut.

The discs D of the contact wheel C are lined up axially on the bushing H. Their hub portions are in direct contact with one another and pressed together by nut J and shoulder L. They may also be permanently bonded together, for instance by cementing, so that they will not come apart even when the nut J is loosened to remove the wheel from the shaft.

The body and mainly the rim portion of each disc D is preferably molded of a plastic material such as soft rubber. This insures positive traction on the abrasive belt A and resilient flexure of this belt at the point of contact with the work piece P. Each disc D is positively centered on the bushing H by a relatively rigid, preferably metallic, circular insert plate Q, which is molded into and substantially covered by the rubber body. This serves also as a reinforcement for the disc, which prevents or contributes to prevent undue expansion of the disc upon high-speed rotation. Such expansion can be additionally prevented by suitable side reinforcements for the disc, made of textile fabric or the like.

The thickness T of the inner or hub portion of each disc D is greater than the width of the outer or rim portions of the disc, but smaller than the amplitude S of the corrugations E formed by said rim portions. As a result, when the hub portions of any two discs D are in contact with one another, the rim portions of the two discs are spaced by slight, but positive distances u.

The fan-shaped corrugations E are formed by molding the rim portion of the disc in form of folds; each fold preferably extending in a radial direction with respect to the center of the disc. The contact wheel can then be dressed repeatedly when its surface has been worn or unbal-

anced by continued use. Such repeated dressing is facilitated by the feature that the reinforcements Q of the discs are covered by and smaller than the discs themselves.

In Figure 5 the folds or corrugations E comprise alternating strips 10 extending in a diagonal direction across the face of the disc and wheel; intermediate strips 11 extending in the opposite diagonal direction; and joints 12 between these strips at their lateral ends; the strips 10, 11 and joints 12 being elongated and radially disposed as mentioned. The form of the different strips 10, 11 is identical as to their width t , angularity x and other features of configuration; this is important mainly if it is intended occasionally to reverse the direction of rotation of the contact wheel.

The amplitude or width S of the corrugations E exceeds the thickness T of the discs approximately by twice the width t of the strips 10, 11, whereby the joints 12 of each disc are located adjacent to but substantially outside the planes y of the sides of the disc. A greater overhang of the joints 12, beyond the sides y would result in a flexibility of the strips which is greater adjacent their ends than in the middle. This in turn would result in unequal actuation of the belt, and improper abrasion of the work piece.

In order to avoid such inequality it is desirable not only to keep the joints 12 adjacent the sides y but also to make the joints 12 somewhat stronger than the body of each strip 10, 11. To some extent such strengthening is inherent in the Z-pattern design. Further, the inside corners 13 between the strips may be rounded off more than the outside edges 14 of the joints 12. The effective hardness of the working area 15 can be made substantially uniform, across the face of the contact wheel, by the expedients mentioned.

At the same time the strips or folds 10, 11 form a continuous zig zag or Z-patterned stripe in each working area 15. They are separated by distances u , whereby each fold can flex individually without substantial interference by other folds. This feature is obtained without any expensive and wasteful cutting operation on the outer surface of the contact wheel. It results in a particularly efficient operation of the abrasive belt.

In this operation the contact wheel C rotates rapidly, whereby its flexible, corrugated rim portion expands centrifugally to some extent. The surface of the wheel is dressed so that it has the necessary flat or special contour at the predetermined speed of rotation. The rotating wheel grips the inside of the abrasive belt A and moves the belt at the predetermined speed, against the resistance of the work piece P. As this work piece is pressed against the belt the abrasive particles remove minute chips of material from the surface of the work piece, and the contact wheel is locally distorted.

It is this distortion of the contact wheel and the related operation of the abrasive belt which is improved by the present design. Due to the Z-pattern of the working surface 15, the moving abrasive belt is exposed to short waves of flexing operations in continuous succession and in a wide range of different directions. This short-wave, wide-range flexing is a definite aid to the operation of abrasive belts, mainly of the fine or finishing types.

Such belts are coated with abrasive particles which are small and spaced by small interstices. They remove a great number of small particles from the surface of the work piece. Therefore

they tend to fill or "load" the interstices rapidly. This tendency leads to the rapid arrival of inoperability or "burning" of an abrasive belt.

This "burning" tendency is strongly counteracted by the special flexing of the belt as described, and the effective life of finishing belts is greatly extended in this manner. I have obtained, for instance, an effective life of 24 contact minutes when testing a contact wheel generally similar to that described above, with an abrasive belt of paper, commercially known as 14 ft. x 4 inch No. 80 ALO-EC-M belt. The test was made on a work piece of low-carbon descaled steel of the grade known as 1015T. The speed was 7350 surface feet per minute. This effective life is materially longer than that which can be obtained with the best applicable contact wheels previously known, under comparable conditions mainly as to the finishing belt, the work piece and the operating speed. The contact wheel used in the test was merely experimental; the effective life of the belt can be lengthened further, by changes applied to the new contact wheel C in a manner which is obvious in view of the present disclosure.

Effective life is one of the most important considerations in the application of finishing belts. However, it may be also important to remove some definite amounts of material from the surface of the work piece. An increase in the amount of material removed during each contact minute can be obtained for instance by using the modified working surface of Figure 6. This increase is usually obtained at the cost of a certain reduction of the effective life of the belt.

In this modified form the distances between the strips 10 are greater than the distances between the intermediate strips 11. This can be achieved very simply by a modified assembly and bonding together of identical discs C. The closely adjoining or abutting strips 11 are less free to flex than are the strips 10. Solid or semi-solid "land" areas are formed in this manner. The range of flexing operations in the belt is decreased.

Another modified assembly is used in Figure 7. Here a further increase in material removed per contact minute is obtained by incorporating serrations 16 in the contact wheel C. In the form as shown, the working surface is interrupted by eliminating the strips 10 in their entirety. In this manner the strips 11 are isolated so that they form projecting teeth of a serrated pattern. The different teeth or strips 11 are lined up to form diagonal "land" or working areas 17 extending helically, across the face of the wheel. The removal of the strips 10 can be achieved by molding or cutting or otherwise. The serrated pattern can be re-established for instance by redressing the surfaces 17 and cutting a deeper groove 18 into the face of the contact wheel between these surfaces.

In comparison with the "finishing" contact wheel of Figure 5 that of Figure 6 is more "aggressive" and that of Figure 7 is much more aggressive." The contact wheels of Figures 6 and 7 may best be operated with relatively coarse belts, in comparison with those for Figure 5. In this manner the amount of material removed is increased and a more adequate effective life of the belt is obtained; the operation is more of the "burnishing, grinding or stock removing" type.

On the other hand the operation of a contact wheel and abrasive belt in accordance herewith can be made as fine and mild as is possible by any

other tools presently available. Figure 8 shows a further modification of the fan-shaped disc which is useful in this respect. Here the corrugations of the rim are wavy rather than sharp-cornered, thereby providing curved or bent portions 19 between the strips 10, 11. The inner and outer curvature 20 of these bent portions 19 may have similar radii, of substantial length in comparison with the width of the disc D. The resulting, wave-patterned working areas 21 have substantially uniform width throughout their length, thereby eliminating the corner joints and reinforcements 12 and enabling all parts of the corrugations to bend still more freely in all directions. The flexibility and belt-cushioning effect of the working areas 21 can be kept uniform along this working area 21, if the wavy folds are long enough, in directions radially of the contact wheel, to eliminate the inequality due to the overhang of the bent portions 19.

The contact wheel of Figure 8 is generally the most yielding one of the different types illustrated. It is comparable, in this respect, with a soft cloth buffing wheel. It can best be used for fine polishing, and for the finishing of sharply curved surfaces. The wheel of Figure 5 is somewhat less yielding and is suitable for work with stronger abrasive belts. The wheel of Figure 6 is still less yielding and is suitable for considerably rougher belts. The wheel of Figure 7 is yielding in manners more similar to those of standard serrated contact wheels. It is suitable for rather aggressive and continued stock removal.

The wheels of Figures 5, 6 and 7 can be made with identical mold equipment. Similar variations of course can be obtained with the wheel of Figure 8.

The grinding wheel according to said Doermann patent can probably be considered as the closest approach of the prior art to the present type of wheels. It is constructed with a "solid" working surface and with a practically uninterrupted coat of abrasives thereon, whereby it is made unsuitable for use as a contact wheel. If the direct coating were removed, and the wheel used to actuate an abrasive belt it would act substantially like a plain, unpatterned, un-

rated contact wheel. Mainly when used with a finishing belt it would "burn" the belt rapidly, in comparison with any of the present wheels. On the other hand, when used with a coarse belt it would not remove stock nearly as rapidly as does, for instance, the present wheel of Figure 7. Even when serrated with grooves of similar contour, it would operate differently.

Persons skilled in the art will be able, upon consideration of this disclosure, to produce further modifications, within the spirit of my invention. I claim:

1. A contact wheel segment consisting in a generally disc-shaped body, the peripheral part of which is elastic and slightly expandable centrifugally and shaped in form of radially extending corrugations, while the central part of the body is thicker than the peripheral part thereof but thinner than the width of the space occupied by the corrugations and comprises rigid, disc-shaped plate means coaxial with and firmly bonded to the body, so that a contact wheel formed of several such segments axially aligned with their central parts in mutual contact and with the corrugations nested together has a body reinforced against excessive centrifugal expansion, and a working surface consisting in stripes which have a corrugated outline and are spaced from one another.
2. A contact wheel according to claim 1, wherein the peripheral part is substantially composed of soft rubber and the rigid plate means is substantially composed of metal.

35 WILLIAM J. COSMOS.
